(57) **CLAIM**

An ornamental design of a needle holder, as shown and described.

DESCRIPTION

FIG. 1 is a top, front, right perspective view of a needle holder, shown in a first configuration, having a compact form and needle cap attached;

FIG. 2 is a bottom, front, right perspective view of the needle holder of FIG. 1, shown in a first condition of use without the needle cap for clarity of disclosure;

FIG. 3 is a front elevation view thereof;

FIG. 4 is a left elevation view thereof;

FIG. 5 is a right elevation view thereof;

FIG. 6 is a rear elevation view thereof;

FIG. 7 is a top plan view thereof;

FIG. 8 is a bottom plan view thereof;

FIG. 9 is a top, front, right perspective view of the needle holder of FIG. 1, shown in a second configuration, having an expanded form and needle cap removed;

FIG. 10 is a bottom, front, right perspective view thereof;

FIG. 11 is a front elevation view thereof;

FIG. 12 is a right elevation view thereof;

FIG. 13 is a rear elevation view thereof;

FIG. 14 is a left elevation view thereof;

FIG. 15 is a top plan view thereof;

FIG. 16 is a bottom plan view thereof;

FIG. 17 is a top, front, left perspective view of the needle holder of FIG. 1, shown in a third configuration, having an expanded form, needle cap removed and syringe barrel extended;

FIG. 18 is a bottom, front, right perspective view thereof;

FIG. 19 is a front elevation view thereof;

FIG. 20 is a right elevation view thereof;

FIG. 21 is a rear elevation view thereof;

FIG. 22 is a left elevation view thereof;

FIG. 23 is a top plan view thereof; and,

FIG. 24 is a bottom plan view thereof.

(Continued)

In the drawings, the equal-length broken lines depicting portions of the needle holder form no part of the claimed design. The equal-length broken line showing of a needle cap, needle and surrounding accompaniments depicts environmental structure that forms no part of the claimed design. All broken lines form no part of the claimed design.
